UNITED STATES PATENT OFFICE.

RICHARD S. MOUSHON, OF PEORIA HEIGHTS, ILLINOIS, ASSIGNOR OF ONE-HALF TO
W. G. HILLER, OF PEORIA, ILLINOIS.

FIREWORKS HOLDER.

Application filed December 16, 1925. Serial No. 75,716.

My invention relates to devices for handling fireworks and the like.

The object of the invention is in the provision of a simple device adapted for use in the firing of the various types of fireworks, including firecrackers, roman candles, etc.

Still another object thereof is in the provision of a simplified device adapted to hold various types of fireworks in such manner as to insure absolute safety to the person firing same.

Yet another object is in the provision of a device fashioned in such manner as to receive various types and sizes of fireworks without adjustment, said fireworks being maintained in the device in a manner to insure safety to the user.

A further object of the invention is in the provision of a fireworks holder fashioned to receive various types and sizes of fireworks therein without adjustment, and in a secure manner, said device including an ejector member adapted to forcibly eject the firework therefrom after same has been fired.

Referring to the drawings—

Fig. 1 shows a side elevation of the device, with portions broken away for a more detail view thereof;

Fig. 2 shows a modification thereof, and Fig. 3 is a plan view looking into the end of the device shown in Fig. 2.

There is shown in the drawings, a handle portion 10 adapted to be grasped by the operator. Slidably attached to the handle portion by means of the pivot 11 and slot 12, is a cylinder 13, the same having a plurality of spring members 14 attached, as at 15 therein, in a manner to receive the lower end of any type of firework that is desired to be held in the device, and discharged therefrom. The handle portion 10 has disposed upon its inner or abutment face, a pointed projection 16, upon which the lower end of the firework is adapted to be seated.

It is thought obvious from the above description that should it be desired to eject the firework from the device, it is necessary only to grasp the cylinder 13 with one hand and with the other hand force the handle portion inwardly, with the result that the projection 16 will assume the dotted line position shown in Fig. 1, with the consequent ejection of the discharged firework.

Likewise, a manual return of the handle portion to its normal position will place

the device in condition to receive another firework.

Referring to the modification shown in Fig. 2, there is, in this view, no ejection means shown, and the cylinder, in this instance described as 17, is firmly attached as at 18 to a handle portion 19. A similar pointed portion 20 provides a seat for the lower end of the firework. The spring tension means in the modification includes a plurality of spring members 21 disposed outwardly of the cylinder, but having their operating or receiving ends 22 projecting through apertures 23 in the cylinder 17. These spring members act in a similar manner to those shown in the other figure, to provide a tension holding means for the firework to be held within the device.

The present device is designed primarily with the idea of safety to the operator, in view of the many accidents that occur to persons holding firecrackers, roman candles and various other fireworks in their hands. Applicant feels that he has developed a device which is not only simple in construction, but also one that does not lessen, in any degree, the pleasure of firing the various types of fireworks and this with a considerably increased degree of safety to the operator.

What I claim is:

1. In a fireworks holder, the combination of a cylindrical receiver, a handle therefor, means for holding a piece of fireworks in the receiver including rigid means for holding the fireworks at the closed end of said receiver and resilient means adapted to engage said fireworks near the open end of said receiver.

2. In a fireworks holder, the combination of a cylindrical receiver, a handle therefor, means for holding a piece of fireworks in the receiver including rigid means adapted to engage the fireworks at the closed end of said receiver and resilient means disposed circumferentially of the receiver and projecting radially thereof to engage said fireworks and position the same within the receiver.

3. In a fireworks holder, the combination of a cylindrical receiver, a handle therefor, means for holding a piece of fireworks in the receiver including a pointed member adapted to rigidly engage the fireworks at the closed end of said receiver and a plurality of longitudinally extending resilient members mounted on the circumference of the re-

ceiver and projecting radially thereof to engage said fireworks near the open end of the said receiver.

4. In a fireworks holder, the combination of a cylindrical receiver, a handle adapted to close one end of the receiver and slide relative thereto, means for holding a piece of fireworks in said receiver including rigid means adapted to engage the fireworks at the closed end thereof, resilient means adapted to engage said fireworks near the open end of said receiver, and means for causing relative movement between the handle and the receiver whereby the discharged fireworks may be ejected from said receiver.

5. A fireworks holder comprising a cylindrical receiver, a handle therefor, said handle forming a slideable closure for one end of the receiver, a pointed member carried by the closure and adapted to engage a fireworks, resilient means carried by said receiver for yieldably holding the fireworks at the open end thereof, and means for permitting the handle closure to slide relative to said receiver to eject a discharged fireworks therefrom.

In testimony whereof I have hereunto affixed my signature.

RICHARD S. MOUSHON.
